UNITED STATES PATENT OFFICE.

HAVILAND H. PLATT, OF WALLINGFORD, PENNSYLVANIA.

INTERNAL-COMBUSTION ENGINE.

Application filed February 20, 1925. Serial No. 10,547.

My invention relates to internal combustion engines, and more particularly to that type of engine in which a charge of fuel is compressed and transferred to a combustion chamber in which it is ignited, the products of combustion being allowed to act upon a piston to cause the latter to do useful work.

One object of the invention is to provide an engine of the above noted type which shall 10 be capable of delivering greater power with a smaller consumption of fuel than hitherto has been attained in engines of similar displacements.

A further object is to provide an engine 15 more compact and lighter in weight than engines of the same rating heretofore constructed.

Another object of the invention is to provide an engine which shall be comparatively 20 cheap to construct and to maintain.

A further object of the invention is to provide an engine in which the number of parts is reduced to a minimum and in which these 25 parts are so arranged that they shall not be subject to disorders nor require frequent inspection and repair.

A still further object of the invention is to provide an engine incapable of backfiring.

The invention further contemplates the 30 provision of a novel method for operating an engine of the above stated type.

These objects and other advantageous ends I secure as hereinafter set forth, reference being had to the accompanying drawings, in 35 which:

Figure 1 is a longitudinal vertical section on the line *a*—*a*, Fig. 3;

Fig. 2 is a transverse vertical section on the line *b*—*b*, Fig. 3; and

Fig. 3 is a horizontal section on the line *c*—*c*, Fig. 1.

With reference to the drawings, my engine may comprise the usual crank case 1 provided with bearings 2 and 3 for a crank shaft 4. 45 The crank shaft may carry the usual fly wheel (not shown), and has in the interior of the casing 1 a crank 5. The shaft 4 also carries in the interior of the casing 1 an eccentric 6 provided with a strap 7 to which 50 is attached a forked eccentric rod 8.

My engine further comprises a cylinder casting 9 which, as shown in Fig. 1, contains

a cylinder whose upper portion 10 is of lesser diameter than the lower portion 11, and within this cylinder is a piston having upper and lower portions 12 and 13 of different diameters adapted respectively to operate in the said upper and lower portions of the cylinder. The piston 12—13 is operatively connected with the crank 5 of the shaft 4 through 55 the usual connecting rod 14. The cylinder and piston preferably are so proportioned that the area of the upper end of the piston is somewhat greater than the effective area of the lower enlarged portion 13.

The cylinder 10—11 is provided with three ports; one 15, at the top of the upper smaller section 10 of the cylinder; another, 16, also in the smaller section 10 but intermediate the top and bottom thereof, and a third, 17, at 60 the top of the cylinder section 11 of greater diameter. Collapsing spring packing rings 18 bearing inwardly against the piston are set in an annular recess at the bottom of the section 10 of the cylinder, and are retained by 65 a segmental follower ring 19, as clearly illustrated; and each of the sections 12 and 13 of the piston is provided with the usual piston rings 20.

In addition to the cylinder 10—11, the casting 9 comprises a cylinder 21, which preferably parallels the said cylinder 10—11, and like the latter has its longitudinal axis in a plane with the axis of the shaft 4. The cylinder 21, as shown in Fig. 1, communicates 70 with the cylinder 10—11 through the ports 15 and 17, and has also an intake port 22, near the bottom thereof, and an exhaust port 23 at the top.

Operative in the cylinder 21 are piston valves 24 and 25, the latter being connected through a wrist pin 26 with the eccentric rod 8, and the two being connected rigidly together through yokes 27 and 28, see Fig. 2, attached respectively to the pistons 24 and 25, and connected together by tie rods 29, 29 which pass slidably through the upper portion of the cylinder casting 9 and the top of the crank case 1. In the cylinder 21 and intermediate the pistons 24 and 25, provision is made for a spark plug 30 or other device for igniting explosive gases in the cylinder.

As shown in Fig. 1, the piston 25 is formed with a passage 31 through which communi-

cation may be established between the ports 22 and 17, the passage 31 being at all times separated from the space between the pistons 24 and 25, and from the crank case.

5 Although in the present instance, I have shown the entire upper portions of the cylinders 10—11 and 21 surrounded by a water jacket 32, the cooling system may be varied, as may be found necessary or desirable, without departing from the invention.

10 The piston valves 24 and 25, like the piston 12, are provided with suitable packing rings 33, and in order to prevent these packing rings from catching upon the edges of the ports 15, 16 and 17, the latter are provided with bridges extending longitudinally of the cylinders, one of these bridges 34 in the port 15 being illustrated in Fig. 3. In this case, the bridge is made hollow to provide a connecting passage 35 between adjacent ends of the water jacket.

15 Assuming the various parts are in the positions illustrated in the drawings and the shaft (4) turning in the direction of the arrow in Fig. 2, the piston 12 has recently passed the top of its stroke. A charge has just been exploded in the combustion chamber or cylinder 21, and it will be noted that the port 17 is shut off by the valve 25 from the combustion chamber, and that the port 15 is partially open so as to permit the products of combustion to expand into the cylinder 10—11 above the piston 12. The piston 24 also shuts off the port 15 from the exhaust port 23 and port 16 is closed.

20 As the piston 12 moves downwardly, the piston valves 24 and 25 move upwardly, thereby further opening both the port 15 and the port 17 and permitting a fresh charge of combustible gases to be drawn through the port 22, the passage 31, and the port 17 into the lower larger section of the cylinder 10—11. Continued downward movement of the piston 12 eventually uncovers the port 16 and permits the escape of the products of combustion from the lesser portion 10 of the cylinder 10—11, the pressure within the upper part of the said cylinder 10—11 and the combustion chamber 21 dropping nearly to that of the atmosphere. Before the piston 12 reaches the lower end of its stroke, the piston valves 24 and 25 reverse their movement, and as the piston 12 passes the bottom of its stroke but before it has risen far enough to close the port 16, the valve element 24 cuts off the port 15 from the combustion chamber, and very shortly thereafter opens said port to the exhaust 23. The piston 12 then closes the port 16, and for the greater portion of its upward stroke forces the products of combustion remaining in the cylinder out through the port 15 and the exhaust port 23.

25 As previously stated, a fresh charge of combustible gases is drawn into the lower enlarged section of the cylinder 10—11

through the downward movement of the piston 13, and when the piston reaches the bottom of its stroke, the annular space in the said enlarged portion 11 of the cylinder has reached its greatest volume and is practically full of fuel. As the piston starts to move upward, the valve element 25 which is moving downwardly, as previously described, shuts off the port 17 from the port 22, and almost immediately thereafter opens the port 17 into the cylinder 21 in the space between the pistons 24 and 25, which space constitutes the combustion chamber, and which, as previously described, has been closed off from the port 15. Under these circumstances, the continued upward movement of the piston 13 compresses the gases in the space between the pistons 24 and 25.

30 When the piston has nearly reached the top of its stroke, the port 15 is closed to the exhaust by the upward movement of the valve element 24, and during the rest of the stroke the remaining products of combustion in the cylinder are compressed to a pressure approximating that of the compression pressure in the combustion chamber. Within a short interval at the top of the piston stroke, the port 15 opens to the combustion chamber, the port 17 closes off from the combustion chamber, and the compressed charge in the combustion chamber is ignited by the spark plug 30. Shortly thereafter, the port 17 is opened to the intake, and the cycle, as described above, is repeated.

35 With an engine constructed as described and illustrated, numerous advantageous results are obtained, among which may be noted the comparatively small number of parts, the comparatively small space occupied, and the low expense of manufacture due to the use of only one cylinder, one piston, one connecting rod, and one crank to perform the service heretofore requiring two of each of these parts. With this construction, also, there is a considerable gain in efficiency achieved by reduction to a minimum of friction and of heat losses and by improvement of volumetric efficiency owing to the fact that the combustion chamber is cut off from the intaking portion of the cylinder whereby the new charge cannot be reduced by re-expansion of old products of combustion remaining in the combustion chamber.

40 A further important gain in efficiency is obtained by proportioning the cylinder and piston as described so that the volume of the annular space swept out by the lower portion of the piston is smaller than the volume displaced by the upper portion of said piston. In this manner, the products of combustion are expanded to a volume greater than that of the original charge; the pressure at release being thereby reduced and work being derived from expansion which would otherwise be lost into the exhaust. Obviously, it may

be desirable, under some circumstances, as where lightness in weight is an essential, to have the effective area of the upper portion of the piston smaller than the effective area of the lower portion, although this reduces the efficiency as indicated above.

Again it is absolutely impossible with the construction shown for backfire to occur, since the intake passage 22 is at no time in direct communication with the combustion chamber.

Obviously the engine is subject to some modification without departure from the essential features of the invention.

I claim:

1. The combination in an internal combustion engine, of a power cylinder having two portions of different diameters; a piston in said cylinder having two diameters to fit the two portions of said cylinder; a valve cylinder; a port opening from said valve cylinder into the larger portion of the power cylinder; a second port opening from said valve cylinder into the smaller portion of said power cylinder; means for controlling said ports; and a port opening from the power cylinder controlled by the piston.

2. The combination in an internal combustion engine, of a power cylinder having two portions of different diameters; a piston in said cylinder; a valve cylinder; a combustion chamber in said valve cylinder; means for connecting said combustion chamber alternately to the two portions of said working cylinder; and a port opening from the power cylinder controlled by the piston.

3. The combination in an internal combustion engine, of a cylinder; a piston in said cylinder; a power space in said cylinder closed in by the head portion of said piston; an annular compression space closed in by an enlargement on the skirt of said piston; a combustion chamber; an opening between said combustion chamber and said power space; a valve element for controlling said opening; a second opening between said combustion chamber and said compression space; a valve element for controlling said second opening; and a port opening from the power cylinder controlled by the piston.

4. The combination in an internal combustion engine, of a power cylinder having two portions of different diameters; a piston in said cylinder having two diameters to fit the two portions of said cylinder; a combustion chamber; a port opening from said combustion chamber into the larger portion of the power cylinder; a second port opening from said combustion chamber into the smaller portion of said power cylinder; means for controlling said ports; and a port opening from the power cylinder controlled by the piston.

5. The combination in an internal combustion engine, of a cylinder having power and compression sections; a piston operative in

both of said sections and having a greater effective area in the power than in the compression section; a combustion chamber; a port between the combustion chamber and the power space; a second port between the combustion chamber and the compression space; and valve means controlling said ports.

6. The combination in an internal combustion engine, of a cylinder having power and compression sections; a piston operative in both of said sections and having a different effective area in the power than in the compression section; a combustion chamber; a port between the combustion chamber and the power space; a second port between the combustion chamber and the compression space; and valve means controlling said ports.

7. The combination in an internal combustion engine, of a power cylinder; a piston in said cylinder; an exhaust port controlled by said piston; a second exhaust port in said cylinder supplementing the piston controlled port; valve mechanism for controlling said second exhaust port; a combustion chamber external to said cylinder; and valve mechanism for establishing and severing communication between said cylinder and combustion chamber.

8. The combination of a power cylinder; a piston in said cylinder; an exhaust port controlled by said piston and a secondary and supplemental exhaust; a second port in said cylinder; a combustion chamber; and valve mechanism arranged to establish and sever communication from said port alternately to the combustion chamber and to the secondary exhaust.

9. The combination, in an internal combustion engine, of a power cylinder having two portions of different diameters, a piston in said cylinder enclosing therein two chambers, a valve cylinder adjacent said power cylinder, a port connecting said valve cylinder with one of said chambers, a second port connecting said valve cylinder with the other chamber, two valves in said valve cylinder controlling said ports, and means external to the valve cylinder for rigidly connecting said valves.

10. The combination, in an internal combustion engine, of a cylinder, a piston in said cylinder, a power space in said cylinder closed in by the head portion of said piston, an annular compression space closed in by an enlargement on the skirt of said piston, a valve cylinder, a port between said valve cylinder and said power space, a valve element in said valve cylinder for controlling said port, a second port between said valve cylinder and said compression space, a second valve element in said valve cylinder for controlling said second port, and means external to the valve cylinder for rigidly connecting said valve elements.

11. The combination, in an internal com-

bustion engine, of a power cylinder having two portions of different diameters, a piston in said cylinder having two diameters to fit the two portions of said cylinder, a combustion chamber, a port opening from said combustion chamber into the larger portion of the power cylinder, a second port opening

from said combustion chamber into the smaller portion of said power cylinder, two valve elements for controlling said ports, and means external to said combustion chamber for rigidly connecting said valve elements.

HAVILAND H. PLATT.
